UNITED STATES PATENT OFFICE.

WILLIAM R. ABERCROMBIE, OF BRIDGEPORT, CONNECTICUT, ASSIGNOR
TO WHEELER & WILSON MANUFACTURING COMPANY, OF BRIDGEPORT,
CONNECTICUT, A CORPORATION OF CONNECTICUT.

SEAM-TRIMMER AND EDGE-BINDER FOR SEWING-MACHINES.

No. 849,347.

Specification of Letters Patent.

Patented April 2, 1907.

Application filed November 7, 1906. Serial No. 342,360.

To all whom it may concern:

Be it known that I, WILLIAM R. ABERCROMBIE, a citizen of the United States, and a resident of Bridgeport, in the county of 5 Fairfield and State of Connecticut, have invented certain new and useful Improvements in Seam-Trimmers and Edge-Binders for Sewing-Machines, of which the following is a specification.

This invention relates to improvements in sewing-machines for simultaneously trimming and binding, wherein the work is trimmed adjacent to the line of seaming, followed by the application of a binding to the trimmed 15 edges of the superposed materials. In machines of this character it has been the common construction to mount the binder-head upon a swinging arm capable of vertical movements at its free end, so that the binder-head could be lifted from its seat in the 20 throat-plate and swung out of operative position or to cut away the throat-plate to the depth of and directly in line with the binder-head, so as to permit of the binder-head being 25 swung in the horizontal plane of its operative position.

It is believed that my present invention embodies the first sewing-machine construction capable of binding and trimming an end-30 less seam wherein the meeting ends of the binding are overlapped. This result I effect mainly by the employment of a trimming mechanism capable of being adjusted into and out of action during the stitching operation in connection with a binder-head capable 35 of adjustment in a direction substantially transverse to the direction of the feed of the material to a position convenient for the severing of the binding and for the convenient 40 manipulation of the severed end of said binding to complete the stitching and binding operation.

In my improved construction I mount the binder-head on a slide plate, so as to be capable 45 of horizontal adjustment in a line transverse to the line of the seam, and provide a locking device which enables the operator to unlock and to adjust such slide plate to inoperative position by simply pushing against 50 the thumb end of a locking-lever, and when the parts are returned to their operative position the locking device is automatically actuated. Thus the operator is enabled to

conveniently manipulate the adjustment of parts and materials for the commencement 55 and completion of the binding operation, and such adjustable control of the binder-head permits the severing of the binding intermediate of and at a point only slightly distant from the line of the needle actuation and 60 the binder-head.

In sewing-machines employed for simultaneously trimming and binding wherein the binder-head is mounted upon a swinging arm and adjustable in substantially the direction 65 of the length of the seam it is necessary to swing the binder-head a much greater distance than is required for the supply of binding necessary for the commencement of the succeeding operation, and as the binder-head 70 is returned to its operative position the excess of binding drawn through the binder-head when adjusting to inoperative position inconveniences the operator in the manipulation 75 of the end of binding severed from the supply to overlap its meeting end. Further, when the binder-head is returned to its operative position, the excess of binding drawn through the binder-head by the previous adjustment must either be severed and go to 80 waste or be drawn back through the binder-head.

In the accompanying drawings, illustrating my invention, in the several figures of which like parts are similarly designated, 85 Figure 1 is a front end elevation of a sewing-machine equipped with my invention; Fig. 2, a rear side elevation of the same; Fig. 3, a portion of the base of the sewing-machine, illustrating, in plan view, the slide-plate and 90 parts carried by it adjusted to their operative positions; Fig. 4, a view similar to Fig. 3, illustrating the slide-plate and parts carried by it adjusted to their inoperative positions; and Fig. 5 a view in perspective of the 95 trimmer throat-plate.

In describing my improvements only such limited reference will be made to the usual well-known parts of the sewing-machine as is deemed necessary for a proper understanding of my invention.

1 is the cloth-plate of the sewing-machine; 2, the overhanging arm; 3, the band-wheel; 4, the needle-bar; 5, the needle; 6, the presser-bar; 7, the cloth-presser; 8, the take-up; 9, 105 the needle-thread tension; 10, the presser-bar

lifter; 11, the loop-taker; 12, the feed-dog, and 13 the shuttle-bobbin.

14 is the trimmer-blade-carrying bar; 15, the trimmer-blade; 16, the trimmer-blade holder; 17, a hand-bracket secured to the trimmer-blade-carrying bar; 18, the trimmer rock shaft; 19, the trimmer rock-shaft lever, and 20 the trimmer rock - shaft lever - pin, which coacts with a notch 21, formed in the trimmer-blade-carrying bar to move said bar vertically in opposite directions through the action of an eccentric 22 upon the forked ends 24 24 of an actuating-lever 25, which in turn is secured to the trimmer rock-shaft 18, said eccentric being secured to the needle-bar-actuating shaft 23.

26 is a spring, one end of which is seated in a pocket 27, formed in the overhanging arm 2, its opposite end bearing against the under side of a bracket 28, which latter is secured to the trimmer-blade-carrying bar 14, said spring causing the cutter - carrying bar when not operatively connected with the pin 20 to be held elevated sufficiently to carry the notch 21 out of range of the oscillatory movements of the pin 20, as when for any purpose it is desired to discontinue the trimming operation. The withdrawal of the pin 20 from the notch 21 is effected by moving the hand-lever 29 in the direction indicated by the arrow 30, said lever carrying with it the connected rock-shaft 18 and lever 19, thus moving the pin 20 out of engagement with the notch 21. The hand-lever 29 is provided with a bracket 31, through which a screw 32 passes loosely and is threaded into the rock-shaft 18 for operatively connecting said rock-shaft with the lever 29.

33 is a spring seated in a pocket 34, formed on the overhanging arm, the upper end of which acts against the under side of an arm 35, formed integral with the lever 29, the spring 33 acting to hold said lever in a direction opposite to that indicated by the arrow 30.

45 In the drawings, Figs. 1 and 2 illustrate the trimmer-blade-carrying-bar 14, disconnected from its actuating mechanism, and when it is desired to connect the trimmer-actuating mechanism with the trimmer-blade-carrying bar the operator, through the hand-bracket 17, moves the trimmer-blade-carrying bar downward until the pin 20 engages the notch 21, thus causing the trimmer-blade-carrying bar, through the connections previously described, to be actuated by the eccentric 22.

36 36 are screws for securing the bobbin-stop 37 to the under side of the throat-plate.

60 The previously-described stitch-forming cloth feeding and trimming mechanisms are the same as are common to the Wheeler & Wilson well-known commercial seam-trimming machine and may be as herein pointed out or of any approved construction, as they 65 form no part of my present invention except

that they, together with the binding mechanism, define the necessary combination for seaming, trimming, and binding the edge of materials by a single operation.

38 is a throat - plate provided with the 70 ledger trimmer-plate 39, trimmer-blade guard 40, guard-plate 41, binder-head seat 42, needle-hole 43, feed-slots 44 44, and holes 45 45, through which latter the throat-plate screws 46 46 pass to secure said plate to the 75 plate 1 of the sewing-machine.

The ledger trimmer-plate 39 comprises a hardened piece of steel set into the throat-plate and against which the cutter-blade acts to sever the material, the guard 40, 80 through the action of the springs 66, forcing the cutter-blade against the edge of the ledger-plate. As the construction and application of the ledger-plate and guard-plate illustrated in the several figures form no part 85 of my invention, a further description of them is deemed unnecessary.

47 is a bracket provided with arms 48 48, which latter are bent around the outer edge of the cloth-plate 1, said bracket being 90 secured to the cloth-plate 1 by a screw 49.

50 is a slide-plate, upon which is mounted the binder-head 51, the scroll-guard 52, tension-pins 53, locking-lever 54, and locking-lever spring 61. The slide-plate 50 is provided with a narrow extended portion 55, provided with a slot 56, through which pass screws 57 57, which latter are threaded into the bracket 47. The screws 57 57 are adjusted to guide, together with the undercut 100 guideways 58 58, the slide-plate 50 in its movements in opposite directions. The lock-lever 54 is pivotally mounted by stud-screw 59 to the upper side of the slide-plate and provided with a thumb end 60, which 105 latter is acted upon by a spring 61, secured by screw 62 to an ear 63, which latter forms a part of the slide-plate 50. The lock-lever 54 is provided with a pin 64, which latter is adapted to enter a notch 65, formed in the 110 bracket 47 for holding the slide-plate 50 and parts carried by it against accidental adjustment when such parts occupy their operative positions.

In the operation of my improved construction 115 the binding is passed from the supply first between as many of the tension-pins as are necessary for the required tension, then through the binder-head, and under the cloth-presser. The machine being started, the material is fed under the cloth-presser to the action of the trimming-blade, then between the folds of the binding to the stitch-forming mechanism. After the stitching has proceeded nearly to the finish of the 125 seam, supposing the seam to be of the endless variety, as when putting in sleeves, the operator moves the lever 29 in the direction indicated by the arrow 30, withdrawing the pin 20 from the notch 21, thus disconnecting 130

the trimmer-blade-carrying bar 14 from its actuating mechanism, followed by pressing against the thumb end of the lever 54, thereby withdrawing the pin 64 from the notch 65 and at the same time moving the slide-plate 50 to the position shown in Fig. 4 with the binding extending from the needle to the binder-head. The binding is then severed between the seam and the binder-head, the portion attached to the material being positioned to overlap the starting end and the seam continued to the end of the binding operation. The operation being completed, the succeeding operation is commenced by first moving the binder-head to its operative position, when the free end of the binding is positioned beneath the presser-foot, and the second operation continued in like manner as the first.

20 The scroll-guard 52, mounted on the slide-plate 50, guides the trimmed-off portions to the right and away from the line of the needle actuation, thus preventing the same from interfering with the binding and stitching operations.

25 While my invention is adapted more particularly for use in connection with machines provided with trimming mechanisms, it is to be understood that it is not limited in this respect, as it may be used in connection with sewing-machines, the productions of which do not require the employment of a seam-trimming mechanism.

What I claim is—

30 1. In a sewing-machine for seam-trimming and edge-binding, a binder-head and a slide-plate upon which said binder-head is mounted, said slide-plate and binder-head being capable of adjustment in a direction substantially transverse to the direction of the feed of the material to a position convenient for the severing of the binding, and for the convenient manipulation of the severed ends of said binding to complete the stitching and binding operation, in combination with a seam-trimming mechanism provided with means for adjusting the trimmer-blade carrier into and out of operative relationship with the actuating mechanism of the sewing-machine during the stitching operation.

35 2. In a sewing-machine for seam-trimming and edge-binding, a binder-head, a throat-plate provided with a seat for said binder-head, a locking-lever, a slide-plate upon which said binder-head and locking-lever are mounted, and a bracket provided with guides for guiding the movements of said slide-plate and with locking means coacting with said locking-lever to lock said slide-plate in operative relationship with the stitch-forming mechanism, said slide-plate and binder-head being capable of adjustment in a direction substantially transverse to the direction of the feed of the material to a position convenient for the severing of the binding, and for

the convenient manipulation of the severed end of said binding to complete the stitching and binding operation, in combination with a seam-trimming mechanism provided with means for adjusting the trimmer-blade carrier into and out of operative relationship with the actuating mechanism of the sewing-machine during the stitching operation.

40 3. In a sewing-machine for seam-trimming and edge-binding, a throat-plate, a binder-head, a locking-lever, a slide-plate upon which said binder-head and locking-lever are mounted, and a bracket or plate to which said lever locks said slide-plate when the latter is adjusted to its operative position relatively to the stitch-forming mechanism, said binder-head being capable of adjustment in a direction substantially transverse to the direction of the feed of the material to a position for the convenient severing of the binding, and for the convenient manipulation of the severed end of said binding to complete the stitching and binding operation, in combination with a seam-trimming mechanism provided with means for adjusting the trimmer-blade carrier into and out of operative relationship with the actuating mechanism of the sewing-machine during the stitching operation.

45 4. In a sewing-machine for seam-trimming and edge-binding, a slide-plate, a binder-head, a scroll-guard and a locking-lever, said binder-head, scroll-guard and locking-lever mounted upon said slide-plate and capable of adjustment in a direction substantially transverse to the direction of the feed of the material to a position convenient for the severing of the binding, and for the convenient manipulation of the severed end of said binding to complete the stitching and binding operation, in combination with a seam-trimming mechanism provided with means for adjusting the trimmer-blade carrier into and out of operative relationship with the actuating mechanism of the sewing-machine during the stitching operation.

50 5. In a sewing-machine for seam-trimming and edge-binding, a binder-head, a locking-lever, a spring for actuating said lever, and a slide-plate, said binder-head, locking-lever and spring being mounted on said slide-plate and capable of adjustment in a direction substantially transverse to the direction of the feed of the material to a position convenient for the severing of the binding and for the convenient manipulation of the severed end of said binding to complete the stitching and binding operation, in combination with a seam-trimming mechanism provided with means for adjusting the trimmer-blade carrier into and out of operative relationship with the actuating mechanism of the sewing-machine during the stitching operation.

55 6. In a sewing-machine for seam-trimming and edge-binding, a throat-plate, a binder-

4
head, a scroll-guard, a slide-plate and a bracket to which said slide-plate is slidably secured, said binder-head and scroll-guard being mounted upon said slide-plate and capable of adjustment in a direction substantially transverse to the direction of the feed of the material to a position convenient for the severing of the binding, and for the convenient manipulation of the severed end of said binding to complete the stitching and binding operation, a locking-lever carried by said slide-plate and coacting with said bracket to lock said slide-plate in operative relationship with the stitch-forming mechanism, said locking-lever being provided with a

thumb end which coacts with said slide-plate to unlock said lever, in combination with a seam-trimming mechanism provided with means for adjusting the trimmer-blade carrier into and out of operative relationship with the actuating mechanism of the sewing-machine during the stitching operation. 20

Signed at Bridgeport, in the county of Fairfield and State of Connecticut, this 30th day of October, A. D. 1906.
